DESIGN FOR A COMBINATION SOAP DISH AND CLEANSER PAD HOLDER

James R. Caldwell, Wooster, Ohio, assignor to
The Wooster Rubber Company, Wooster, Ohio

Application November 19, 1947, Serial No. 142,644

Term of patent 14 years

(Cl. D4—3)

To all whom it may concern:

Be it known that I, James R. Caldwell, a citizen of the United States, residing at Wooster, in the county of Wayne, and State of Ohio, have invented a new, original, and ornamental Design for Combination Soap Dish and Cleanser Pad Holder, of which the following is a specification, reference being had to the accompanying drawing, forming part thereof, wherein:

Figure 1 is a top plan view of the holder, embodying my new design.

Figure 2 is a side view of the same.

Figure 3 is an end view of the same.

The side of the holder opposite that shown in Figure 2 is identical therewith. Likewise, the end of the holder opposite that shown in Figure 3 is identical therewith.

I claim:

The ornamental design for a combination soap dish and cleanser pad holder, substantially as shown and described.

JAMES R. CALDWELL.
